2 Sheets-Sheet 2

UNITED STATES PATENT OFFICE.

HARRY STEVENS, OF BANGOR, MAINE.

MUSIC-LEAF TURNER.

Application filed December 12, 1924. Serial No. 755,528.

This invention relates to improvements in music leaf turners and has for its principal object to provide a simple and efficient means whereby the person playing the piano may easily and efficiently turn the sheets of the music being played without necessitating the removal of the hands from the keys of the piano, the device being adapted to be controlled by a suitable foot pedal.

One of the important objects of the invention is to provide a music leaf turner of the above mentioned character, wherein means is provided for turning one sheet of music at a time, means being further provided for returning the sheets to their original position after the same have all been played.

A further object of the invention is to provide a music leaf turner of the above mentioned character, which is simple in construction, inexpensive, strong and durable and furthermore adapted for the purposes for which it is designated.

Other objects and advantages of this invention will become apparent during the course of the following description.

In the accompanying drawings forming a part of this specification and in which like numerals designate like parts throughout the same:

Figure 1 is a fragmentary front elevation showing the arms with the sheet engaging clamps associated therewith and the casing secured on the front of a piano.

Figure 2 is a rear elevation.

Figure 3 is a fragmentary side elevation of the foot lever and the co-related parts associated therewith.

Figure 4 is a sectional view taken approximately on line 4—4 of Figure 3.

Figure 5 is a detail of the shaft.

Figure 6 is a front elevation of the casing with the cover removed showing the shaft mounted therein and the inner ends of the arms.

Figure 7 is a sectional view taken approximately on line 7—7 of Figure 6.

Figure 8 is a front elevation of the sheet music engaging means.

Figure 9 is a sectional view taken approximately on line 9—9 of Figure 8, and

Fig. 10 is a detail section taken substantially on the line 10—10 of Fig. 6.

In the drawings, wherein for the purpose of illustration is shown the preferred embodiment of my invention, the numeral 1

designates a casing which is secured on the front of a piano A by any suitable fastening means. Extending vertically within the casing 1 is a rotatable shaft 2. The same is 60 journaled in suitable bearings as is clearly illustrated in Figure 6. The lower end of the shaft 2 is threaded as illustrated at 3 and the purpose thereof will hereinafter be more fully described.

A pinion 4 is fixed on the shaft 2 adjacent the upper end thereof and the same engages a suitable pinion 5 which is supported on the forward end of a shaft 6 which extends transversely through the front of the piano 70 and through the casing. The rear end of the shaft 6 is journaled in a suitable bracket 7 secured on the rear face of the front of the piano.

A pinion 8 is keyed on the rear end of the 75 shaft 6 and cooperating therewith is the segmental gear member 9 which is pivotally supported on the lower portion of the bracket 7 as at 10. The segmental gear member 9 is operable through the medium of an elongated rod 11 which extends across the rear face of the front of the piano, the same being secured at one end to the segmental gear member 9 and at its opposite end to the ends of the arm 12 of a bell crank lever 13 as at 14. The bell crank lever 13 is pivotally supported on the rear face of the front of the piano as at 15 and the other arm 16 is adapted for vertical movement through a 85 suitable guide member 17.

A foot lever 18 extends through a suitable opening 19 provided in the bottom of the front of the piano and is pivotally supported intermediate its ends as at 20 on the bracket 21 which also extends through the opening 95 19. The outer end of the foot lever 18 is provided with a treadle 22 and the inner end of the lever is pivotally connected to the lower end of a vertically extending rod 23 as illustrated at 24. A flat metal bar 25 is 100 pivotally supported intermediate its ends in the upper bifurcated or forked end 26 of a vertically extending supporting standard 27. One end of the flat bar 25 is operatively connected to the upper end of the rod 23 as indicated generally at 28 while the other end of the flat bar 25 is connected to the lower end of a vertically extending rod 29 preferably in the form of a piece of wire. The upper end of the wire rod 29 is bent around 110 the lower end of an additional vertically extending rod 30 and engages the nut 31 which

is threaded on the lower threaded end of the rod 30. The upper end of the rod 30 is connected to the end of the arm 16 of the bell crank 13 through the medium of a ball and socket joint 32. A coil spring 33 is associated with the segmental gear member 9 for normally holding the same in the position shown in Figure 2 and whereby the co-related parts are also held in their normal positions.

A pair of horizontally extending arms 34 and 35 are provided on their inner ends with the sleeves or hubs 36 and 37 respectively, the same being adapted to be disposed on the lower portion of the shaft 2 whereby the arms are adapted for swinging movement thereon. The outer end of each arm carries thereon a sheet or leaf clamping member designated generally by the numeral 38 and the same comprises a plate 39 which is permanently secured to the outer end of each arm, a clamping plate 40 being pivotally supported on the plate 39 and held in cooperative relation therewith by means of the spring 41. A rubber head 42 is associated with the back of each plate 39 whereby the same is prevented from coming in contact with the front of the piano. The manner in which the sheet clamping members are associated with the sheets of music is clearly illustrated in Figure 1.

The upper portion of the hub 36 is provided with a cut out portion 43 and the lower portion of the hub 37 which is disposed above the hub 36 is also provided with a similar cut out portion 44. These cut out portions are furthermore arranged diametrically opposite each other as is illustrated in Figures 6 and 7 and the purpose thereof will hereinafter be more fully described. A pin 45 extending laterally from the shaft 2 adjacent the lower threaded end 3 thereof is adapted to cooperate with the cut out portions 43 and 44 of the sleeves or hubs 36 and 37 respectively, whereby the arms 34 and 35 are adapted for swinging movement in the manner to be presently described.

The shaft 2 is further adapted for vertical movement within the casing 1, and to this end, I provide a plate 46 on the bottom of the bearing bracket for the lower end of the shaft, the plate 46 having one end thereof in engagement with the threaded portion 3 of the shaft and it is obvious that when the shaft is rotated, the plate 46 will engage the threaded portion 3 of the shaft and cause the shaft to move vertically.

The operation of my improved music leaf turner may be briefly stated as follows: Normally the arms 34 and 35 are disposed in the position shown in Figure 1 of the drawing, the sheet engaging clamps associated with the outer ends of the arms being attached to successive sheets of music placed on the front 65 of the piano and to further support the

sheets of music, a spring clip 48 is provided. When it is desired to turn the sheet which is attached to the outer ends of the arms 34, so that the reverse side of the sheet may be played, the foot lever 18 is depressed by stepping on the treadle 22 causing the inner end of the foot lever to move upwardly and engage the lowermost notch formed in the inner end of the bracket 21 as illustrated at 47. The inner end of the foot lever 18 moving upwardly will cause a pivotal swinging movement of the segmental gear member 9 in the direction of the arrows for substantially one half the distance of the gear teeth of the segmental gear member 9 and this will cause the rotation of the shaft 6 through the medium of the pinions 4 and 5, the shaft 2 will be rotated and the plate 46 cooperating with the threaded end 3 of the shaft will raise the latter. The pin 45 carried by the shaft 2 will in the first instance be in engagement with the cut out portion 43 of the hub 36 whereby the arm 34 will swing in a horizontal plane and cause the sheet which is attached to the clamping member carried by the outer end of the arm 34 to be turned over. By depressing the foot lever further so that the inner portion of the foot lever is moved upwardly another notch, the segmental gear member is caused to travel the other half of its entire distance causing the shaft 6 to rotate and simultaneously rotating the shaft 2. Simultaneously, the shaft is raised vertically by means of the threaded portion 3 and the plate 46 whereby the pin 45 will be raised out of engagement with the cut out portion 43 of the sleeve 36 and moved into engagement with the cut out portion 44 of the sleeve, or hub 37 and thereby enable the arm 35 to be swung in a horizontal plane so that the sheet which is attached to the clamping member 38 associated with the outer end of the arm 35 will be turned over.

The purpose of the ratchet teeth 47 is to hold the foot lever in the desired adjusted position 105 as to prevent the accidental return of the arms to their normal position. By disengaging the foot lever 18 from the ratchet teeth 47, the spring 33 will return the segmental gear member 9 to its normal position and simultaneously cause the arms 34 and 35 to be successively returned to their normal positions.

The provision of a music leaf turner of the above mentioned character, will obviate the necessity of the person playing the piano having to remove their hands from the keys of the piano in order to turn the sheets of the music whenever it becomes necessary. It will only be necessary to step on the treadle 22 of the foot lever 18 when it is desired to turn over one of the sheets of the piece of music being played. Furthermore, the parts of my improved music leaf turner are so arranged as not to affect the appearance of the 130

piano and may be easily and efficiently secured in position on a piano.

While I have shown the preferred embodiment of my invention, it is to be understood that various changes in the size, shape and arrangement of parts may be resorted to without departing from the spirit of the invention and the scope of the appended claims.

Having thus described the invention, what I claim is:—

1. A music leaf turner comprising a rotatably mounted shaft, a pair of superposed arms having hub portions on the shaft and provided with diametrically opposed notches when the arms extend in the same direction, threads formed on one end of the shaft, a stationary feed member engaging said threads, a pin extending laterally from the shaft and adapted to engage the notch in the hub of one arm when the shaft is lowered so that when the shaft is rotated, a half turn, said pin will engage in the notch of the hub of the other arm, a pinion keyed on the shaft adjacent the other end, a pinion having a plurality of teeth for engagement with the first mentioned pinion whereby said first mentioned pinion may slide transversely of the axis of the second pinion upon rotation of said pinions because of the threads engaging the feed member, a second shaft on which the second pinion is fixed, a third pin-

ion on the second shaft, a rockable gear segment in mesh with the third pinion, and means for rocking said gear segment. 35

2. A music leaf turner comprising a rotatably mounted shaft, a pair of superposed arms having hub portions on the shaft and provided with diametrically opposed notches when the arms extend in the same direction, 40 threads formed on one end of the shaft, a stationary feed member engaging said threads, a pin extending laterally from the shaft and adapted to engage the notch in the hub of one arm when the shaft is lowered so that when the shaft is rotated a half turn, said pin will engage in the notch of the hub of the other arm, a pinion keyed on the shaft adjacent the other end, a pinion having a plurality of teeth for engagement with 45 the first mentioned pinion whereby said first mentioned pinion may slide transversely of the axis of the second pinion upon rotation of said pinions because of the threads engaging the feed member, a second shaft on 50 which the second pinion is fixed, a third pinion on the second shaft, a rockable gear segment in mesh with the third pinion, a link engaged with the gear segment, a rockable mounted bell crank engaged with the link, 55 and means for rocking the bell crank. 60

In testimony whereof I affix my signature.

HARRY STEVENS.
